(57) **CLAIM**

The ornamental design for an LED video light, as shown and described.

DESCRIPTION

FIG. 1 is a perspective view of an LED video light, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view with an accessory assembled thereof;

FIG. 10 is a perspective view with another accessory assembled thereof;

FIG. 11 is an enlarged view of portion of FIG. 1 thereof;

FIG. 12 is a perspective view with an accessory assembled thereof; and,

FIG. 13 is a perspective view with another accessory assembled thereof.

The broken lines shown in the drawings illustrate portions of the LED video light that form no part of the claimed design.

1 Claim, 13 Drawing Sheets
